UNITED STATES PATENT OFFICE.

GEORGE A. RITZ, OF ROCHESTER, NEW YORK.

SETTEE AND ARTICLE-CARRIER.

1,251,424.

Specification of Letters Patent. Patented Dec. 25, 1917.

Application filed June 15, 1917. Serial No. 174,871.

To all whom it may concern:

Be it known that I, GEORGE A. RITZ, a citizen of the United States, residing at Rochester, in the county of Monroe and State 5 of New York, have invented certain new and useful Improvements in Settees and Article-Carriers; and I do hereby declare the following to be a full, clear, and exact description of the invention, such as will enable others skilled in the art to which it 10 pertains to make and use the same, reference being had to the accompanying drawings, and to the letters and figures of reference marked thereon, which form a part 15 of this specification.

This invention relates to new and useful improvements in sections for receptacles for receiving newspapers, wrappers, or material of any kind and adapted, after receiving its 20 contents, to be housed within a settee or other inclosure.

More specifically, the present invention consists in the provision, in connection with a settee, of a receptacle which is connected 25 by a cable or rope to a drum upon which the cable is adapted to wind, the drum being spring-actuated and adapted to permit the cable or rope to be unwound and to wind up the same automatically when it is desired to 30 cause the receptacle to be drawn back toward the settee.

The invention comprises various other details of construction, combinations and arrangements of parts which will be herein 35 after fully described, shown in the accompanying drawings and then specifically defined in the appended claims.

I illustrate my invention in the accompanying drawings, in which:—

40 Figure 1 is a rear elevation of a settee with the rear portion closed and within which the receptacle is adapted to be contained.

Fig. 2 is an enlarged vertical section, transversely and vertically through the settee 45 showing the receptacle therein in end elevation.

Fig. 3 is a top plan view illustrating the crib or receptacle withdrawn and resting upon a track.

50 Fig. 4 is an enlarged detail view, partly in section, showing a spring for causing the reel to wind up the rope or cable, the spring being put under tension as the crib or receptacle is withdrawn from the settee.

55 Reference now being had to the details of the drawings by letter, A designates a settee

in connection with which my apparatus is preferably employed, although it will be understood that it may be used in connection with any housing or inclosure. Said 60 settee has a chambered portion underneath the seat and has an open bottom A' along the marginal edges of which are bars B with rollers B' journaled therein and which support a platform C. Said platform forms a 65 support for the crib or receptacle D, having wheels D' journaled upon the axles thereon. Said receptacle, for convenience in withdrawing the same from the settee, is provided with handles E. A closure, designated 70 by letter P, to the opening in the settee is provided with handles P', as shown clearly in Fig. 1 of the drawings, and is held in place by means of the buttons R.

Mounted in suitable bearings H', fastened 75 to the rear of the settee, is a shaft H which has two reels, designated by letter I, mounted thereon, and K is a casing over said shaft and fastened to the rear of the settee and provided with openings K' through which 80 the cables or ropes N pass which are secured to and wind about said reels and are also attached to the eyebolts O, secured to the wall of the crib or receptacle D. A spring L, shown in Fig. 4 of the drawings, is 85 mounted upon the shaft H and within a hollow shell L' which is fixed to the shaft and its other end is secured to the reel I and forming means whereby the reel may be put under tension as the rope unwinds from 90 the reel and serves as means for rewinding the rope or cable upon the reel when it is desired to cause the receptacle to be drawn back toward the settee.

Pivots connected to the platform C are 95 the spikes Q, shown clearly in Fig. 1 of the drawings, and which are adapted, when swung down at an angle to the bottom upon which they are mounted, to hold the same in an adjusted position. Tracks T are positioned adjacent to the settee and afford means upon which the truck may run without being obstructed.

In operation, when the receptacle is not in use, it is positioned underneath the settee 105 in the manner shown in Fig. 2 of the drawings, the latter having the appearance of an ordinary settee which may be an ornament to a place where it is located and which may be positioned at any convenient distance 110 from the place where the papers or other objects desired to be placed in the receptacle are,

located. When it is desired to withdraw the receptacle from the settee, the closure P is removed and, by pulling upon the handles E, the receptacle may be withdrawn from 5 the settee and, as the receptacle is withdrawn to a location where it is desired to receive its contents, the ropes will unwind from the reels, putting the same under sufficient tension to cause the receptacle to be drawn 10 back toward the settee when the operator releases the same. In the event of the crib or receptacle D having been withdrawn from the settee and should it be desired to return the receptacle to its place within the settee, 15 a platform C may be rolled out and held by spikes Q, upon which platform the receptacle may be wheeled and after which the platform with the receptacle thereon may be rolled back in place, as shown in 20 Fig. 2 of the drawings.

While I have shown a certain application of my invention in connection with my settee and which is designed especially for receiving newspapers, bundles, etc., and causing 25 the receptacle to be held within an ornamental inclosure, such as a chambered seat, it will be understood that I do not confine myself to any particular detailed construction of apparatus in connection with which 30 the device is used, as obviously it may be

employed for various purposes and may be altered in various ways without departing from the spirit of the invention.

What I claim to be new is:—

1. In combination with a housing, rollers 35 journaled in the lower portion thereof, a platform movable within said housing upon said rollers, means for holding the platform stationary, a wheeled receptacle, a spring-pressed reel upon the housing, and a cable 40 adapted to wind about said reel and connected to the receptacle, as set forth.

2. In combination with a housing having rollers mounted in the lower portion thereof, a platform movable upon the rollers, a stop 45 to limit the inner movement of the platform, the latter projecting outside the housing, spikes pivotally mounted upon the portion of the platform which projects outside the housing, a wheeled receptacle supported 50 upon the platform, a spring-pressed reel, and a cable winding about the reel and fastened to said receptacle, as set forth.

In testimony whereof I hereunto affix my signature in presence of two witnesses.

GEORGE A. RITZ.

Witnesses:

WILLIAM H. A. KRUBRADY,
LUTHER S. LAKE.
